UNITED STATES PATENT OFFICE

JOSEPH O. CADIEUX, OF MERIDEN, CONNECTICUT, ASSIGNOR, BY MESNE ASSIGNMENTS, TO CONNECTICUT TELEPHONE & ELECTRIC COMPANY, INC., OF MERIDEN, CONNECTICUT, A CORPORATION OF DELAWARE

TELEPHONE-INSTRUMENT SWITCHING

Application filed April 29, 1929. Serial No. 359,124.

My invention relates generally to telephones and more particularly to such constructions adapted for use in apartment houses and the like. The present invention is concerned with the switch for controlling the circuit and which is commonly termed the hook switch because it is actuated by the receiver when it is hung up or removed from the hook. Certain features of the present invention are illustrated and described in my former application #282,102, of which this is a partial continuation.

One object is to provide a simple but compact and reliable construction which can be readily wired.

Another object is to provide a construction which is adapted to installation in various ornamental designs.

Another object is to provide a switch which is actuated either by the usual act of hanging the receiver on the hook or by the act of merely releasing or dropping the receiver.

Another object is to provide a construction which can be readily inspected and repaired.

In the preferred form I employ a housing or casing which has a front portion which carries the transmitter and the automatic switch and signal mechanism, as shown in my former application. The back portion of the casing is adapted to be secured to the wall and carries the circuit terminals and connections leading to the instrument. The two parts of the casing are provided with plug-in blades for convenience in connection and installation as set forth and claimed in my former application.

The front part of the casing is preferably formed of insulating material and provided with a rearwardly extending boss which supports the spring contacts of the switch and some of the circuit terminals. The switch actuating lever is pivoted on a tubular stud mounted on the front of the casing. This stud has a slotted end for receiving the loop of the telephone receiver at the proper position to engage the front end of the switch lever. An auxiliary lever is pivoted within the casing and has one end connected with

the switch lever and the other end connected with the receiver cord, so that the weight of the receiver can be employed to hold the switch in the normally active position, whether the receiver is properly hung on the hook or simply left hanging.

The details of the construction will be understood from the following specification:

Fig. 1 is a rear view of such parts of the instrument as embody the improvements of the invention claimed herein.

Fig. 2 is a vertical transverse sectional view of the same but also shows a fragment of the back plate or wall plate.

Fig. 3 is a horizontal section or plan view.

Fig. 4 is a fragmentary vertical sectional view showing the parts of the casing which support the switch and switch lever.

Fig. 5 is a side view of the tubular stud and switch lever carried thereby.

The front member 10 of the casing may be of any suitable design and formed of any suitable material, preferably insulating.

The back plate 11 is adapted to be secured to the wall. The front plate is provided with a peripheral flange 12 and the parts are preferably held together by screws and telescopic members 13.

At the back of the front wall is a ledge 14 on which is mounted a number of terminals and plug-in blade members such as 15 adapted to engage cooperating stationary sockets carried by the back plate. A terminal plate, such as 16, may also be secured to this ledge 14 for effecting various electrical connections.

The pedestal or boss 17 projecting rearwardly from the front wall of the casing serves to support spring contact fingers, such as 18, 19, 20 and 21 of the usual type. Screw threaded sockets 22 are preferably bedded in the boss 17 to receive the screws 23 which support the contact fingers. The boss 17 has a groove 24 and the spring contact fingers are mounted in this groove and project toward the center of the casing. This serves as a very convenient method of attaching the contact fingers. The groove divides the pedestal into two parts and one pair of contact fingers is supported on each

boss. Electrical connections preferably in the form of flat strips 25 are connected to the switch contacts by screws 23, etc.

The switch operating lever 26 is pivoted 5 on the pin 27 within the tubular stud 28. A spring 29 wound on the pin 27 tends to lift the outer end of the lever 26. This stud 28 passes through the front plate 10 and is secured in place by a nut 30 which may also 10 serve to support other elements (not shown). The front wall is provided with a hole 31 through which the shank of the stud 28 extends and recesses 31' are provided to receive the ends of the pivot pin 27 so as 15 to prevent the stud from turning on the front plate.

The receiver 32 of any suitable type is provided with a loop or eye member 33 adapted to be hung onto the front end of 20 the lever 26. The stud 28 is provided with a shield member 34 which protects the other end of the switch actuating lever and leaves a slot 28' which serves to hold the receiver in place. The cord 35 of the receiver extends 25 through a passage 12' and has its terminals 36 and 37 secured to the proper terminal pieces in the casing.

An auxiliary lever 38 is provided on the post 39 in the casing and has one end forked 30 to engage the switch lever 26. The other end of the lever 38 is connected by a tie 41 to the receiver cord, so that when the weight of the receiver pulls on the cord, the lever 38 is tilted to the position shown in Figs. 35 1 and 2, which is the same that it occupies when the receiver hangs on the hook in the usual manner. The stud 12^a serves as a stop for the lever 38 when the weight of the receiver is on it.

40 It will be seen that the switch actuating lever 26 and spring 29 and pin 27 may be assembled in the stud 28 so that these parts may be handled as a unit in the assembling of the construction.

45 It will be seen that the switch contacts and operating parts and connections are all exposed and readily accessible when the rear plate of the casing is removed.

Various changes in details of construction 50 may be made without departing from the principle of the invention.

I claim:

1. In a telephone, an insulating casing having a projecting boss, a number of switch 55 springs supported thereon, a pivoted hook lever projecting through the casing, a jack lever pivoted within the casing and having one arm coacting with said hook lever, a receiver adapted to be supported on said hook 60 lever, and having a cord connected to said jack lever.

2. In a telephone, a casing, a switch mounted therein, a tubular stud secured to said casing, a hook lever pivoted in said stud 55 and having one end projecting for receiving

a telephone receiver and the other end for actuating said switch.

3. In a telephone, a casing, a switch therein, a tubular stud projecting from said casing, a channel-like lever having a pivot in 70 said stud and actuating said switch, and a spring mounted on said pivot within said channel-like lever, for normally holding said lever in actuating position.

4. In a telephone, a casing having an opening with lateral recesses alongside of the opening, a tubular stud secured in said opening, a pivot pin passing through said stud with the ends in said recesses and a switch lever pivoted on said pin. 75

5. In a telephone, a casing, a tubular stud mounted thereon and extending externally thereof, a switch, a lever pivotally mounted in said stud for actuating said switch, a receiver mounted on said stud and adapted to 80 work said lever on its pivot, and a shield integrally formed on the outer end of said stud for retaining the receiver thereon.

6. In a telephone, a casing, a switch, means for operating said switch, including a plurality of pivoted levers, one of which levers extends externally of said casing, means carried by one of said levers for normally holding said levers in operative position, and means adapted to engage the extension end 95 of said externally extending lever for working said levers into operative position. 90

7. In a telephone, a casing, including a removable front wall, a switch, pivoted levers for actuating said switch and a device for 100 operating said levers, said switch, levers and operating device mounted on said front wall.

8. In a telephone instrument, a casing having a cord passage in one edge, a switch mounted within the casing, an actuating lever for the switch having a portion projecting from the casing, a receiver having means for suspending it from said lever, a cord connected to said receiver and extending through said passage and means for connecting said 110 cord with the said lever within the casing for restoring the signal circuit by pulling on said cord.

9. In a telephone instrument, a casing having a cord passage, a switch mounted within 115 the casing, an actuating member for the switch having an external projection, a receiver having means for supporting it on said member, a cord connected to said receiver and extending through said passage 120 and a lever pivoted within the casing and connected to said cord and coacting with said switch actuating member for restoring the signal circuit by pulling on said cord.

10. In a telephone instrument, a casing, a 125 switch within the casing, a switch actuating member extending outwardly through the casing front for supporting a receiver, a pivot post in the casing, an auxiliary lever mounted on the post and coacting with said switch 130

actuating member and a receiver having a cord connected to said lever for tilting said lever on said post to actuate said member.

11. In a telephone, a casing, a switch in the casing, a lever for actuating said switch, an auxiliary lever having one end engaging said actuating lever, a spring coacting with one of said levers for tending to hold the switch in one position, a receiver having a cord anchored in the casing and connected to the auxiliary lever so that a pull on the cord will restore the switch and means for supporting the receiver on the actuating lever.

12. A telephone instrument having a casing, a switch in the casing, a tubular support projecting through a wall of the casing and having a slot in its outer end, a switch actuating member extending into said tubular support, a receiver and means for supporting said receiver on said actuating member in said slot.

13. In a telephone instrument, a casing having a pair of spaced bosses projecting therefrom, spring switch contact fingers mounted between said bosses with their stationary ends bent over the outer ends of the bosses and having anchorage devices extending into the bosses and means for actuating the switch fingers.

14. In a telephone instrument, a casing having two projecting insulating bosses, a pair of spring contact fingers anchored to the outer end of one boss, a second pair of contact fingers having ends anchored to the outer end of the other boss, an actuating member coacting with said contact fingers and a receiver adapted to be supported by said actuating member.

JOSEPH O. CADIEUX.

- actuating member and a receiver having a cord connected to said lever for tilting said lever on said post to actuate said member.
11. In a telephone, a casing, a switch in the casing, a lever for actuating said switch, an auxiliary lever having one end engaging said actuating lever, a spring coacting with one of said levers for tending to hold the switch in one position, a receiver having a cord anchored in the casing and connected to the auxiliary lever so that a pull on the cord will restore the switch and means for supporting the receiver on the actuating lever.
12. A telephone instrument having a casing, a switch in the casing, a tubular support projecting through a wall of the casing and having a slot in its outer end, a switch actuating member extending into said tubular support, a receiver and means for supporting said receiver on said actuating member in said slot.
13. In a telephone instrument, a casing having a pair of spaced bosses projecting therefrom, spring switch contact fingers mounted between said bosses with their stationary ends bent over the outer ends of the bosses and having anchorage devices extending into the bosses and means for actuating the switch fingers.
14. In a telephone instrument, a casing having two projecting insulating bosses, a pair of spring contact fingers anchored to the outer end of one boss, a second pair of contact fingers having ends anchored to the outer end of the other boss, an actuating member coacting with said contact fingers and a receiver adapted to be supported by said actuating member.
